UNITED STATES PATENT OFFICE

HARRY W. LORESCH, OF O'HARA TOWNSHIP, ALLEGHENY COUNTY, PENNSYLVANIA

BURIAL VAULT

Application filed July 25, 1928. Serial No. 295,236.

In modern practice, burial vaults are used, instead of the old wooden "rough boxes" to contain the casket in the grave.

The wooden rough boxes quickly decay, permitting the graves to fall in, and furthermore they were not water-tight—a most important consideration.

Burial vaults are formed of concrete or other plastic material and have their lids sealed in place. The concrete is frequently reinforced with metal.

However the concrete even when reinforced, tends to crack, either from the weight of the settling of the earth or from other causes, such as blasting in excavating nearby graves, so that water gains access to the casket.

Therefore, one of the objects which I have in view is the improvement in the structure of burial vaults so that they will remain permanently water-tight.

For the accomplishment of this purpose I embed in the plastic material of which the body of the vault is formed a metal or other waterproof box whose walls and bottom will prevent the entrance of water through cracks or breaks in the plastic material.

A similar but shallower and inverted box or pan is embedded in the material of the lid, and I provide a new and improved seal for the lid which permanently prevents the entrance of water between the lid and the vault.

I provide a new and improved metal reinforcement of the burial vault.

Other novel features of construction, and also of arrangement of parts will appear from the following description.

In the accompanying drawings wherein I have illustrated a practical embodiment of the principles of my invention, Fig. 1 is a view partially in side elevation and partially in longitudinal section showing the burial vault with its lid in place.

Fig. 2 is an enlarged detail in vertical section showing the sealed joint between the vault and its lid.

Fig. 3 is a detail in section showing the attachment of the reinforcement to the metal box or pan.

Fig. 4 is a broken inverted plan view of the lid with the embedded parts shown in dotted lines.

Fig. 5 is a perspective of the pan which is embedded in the material of the lid.

Fig. 6 is a perspective of the box which is embedded in the material of the vault.

Fig. 7 is a view similar to Fig. 2 but showing a modification.

Referring to the drawings, the vault 1, is in the form of a rectangular container cast or otherwise formed of concrete or other suitable plastic material.

For convenience I will use the term "concrete" to include all such suitable material.

Embedded in the concrete of the vault is the metal box 2 which may be of sheet metal of rust-proof character.

The box 2 may be pressed integrally or the metal may be properly cut and its ends and sides bent up and united with a water-tight joint, as for instance by soldering or welding.

The concrete of the walls and bottom of the vault 1 is reinforced by embedded metal both inside and outside of the box 2, and this reinforcement is preferably attached to the box 2 and in such a manner as to be spaced from the latter to permit the concrete to flow into the spaces between the reinforcement and the box.

Thus I may and preferably do employ an expanded metal reinforcement 3 which is provided at regular intervals with ribs 4 which may be arranged to rest against the inner and outer surfaces of the box 2 and thus span the body of the expanded metal 3 away from the surfaces of the box.

The ribs are preferably attached to the box, and this attachment may be by means of wires 5 soldered or otherwise secured at their centers to the box 2 and with their end portions bent about the ribs and twisted together as shown in Fig. 3. Or the ribs may be soldered or welded to the box as indicated at 6 in Fig. 3.

The expanded metal is continuous in its extent over the entire surface of the box, both within and without the latter, and also over the edges thereof, the sheets of expanded metal being overlapped and wired, as indi-

cated at 7 in Fig. 3, or otherwise connected together to make the reinforcement continuous.

To assist the flow of the concrete when the latter is poured, the ribs 4 are vertically disposed against the walls of the box 2.

The concrete of the vault completely covers the metal box and the metal reinforcement.

The walls of the box and the adjacent reinforcement are flared outwardly at the top so as to be positioned near the outer surface of the vault to provide clearance for the lid pan and reinforcement, as shown in Fig. 2.

In Fig. 7 the arrangement is reversed with the box and vault reinforcement inside of the lid parts.

The lid 8 is also cast of concrete and its central portion is thicker to form the boss 9 which fits down within the upper end of the vault.

The perimetral edge of the lid is provided with a metal band 10 which depends and telescopes downwardly over the vault, as illustrated in Figs. 1, 2 and 7.

This band is supported and secured in place by the framework formed of channel irons 11 embedded in the material of the lid.

The structure of the band and its supporting frame per se is not a part of my present invention, but is more fully illustrated and described in Letters Patent of the United States No. 795,527, issued on July 25, 1905 to John F. Loresch.

12 represents the inverted metal pan or shallow box which is embedded in the concrete of the lid 9 and is completely surrounded by the reinforcement of expanded metal 3a having ribs 4a which bear against and are secured to the pan 12 in like manner as in the case of the box 2 and the reinforcement 3 of the vault 1.

The edges of the pan 12 and the encompassing reinforcement 3a protrude downwardly from the material of the lid into the channel 13 which is formed between the perimetral edge of the central portion 9 of the lid and the band 10, thus forming a continuous metallic tongue.

The top edge of the vault is provided with a relatively deep groove 14 into which said tongue depends. The groove 14 extends down within the box 2 of the vault.

The outer top edge of the vault is also preferably rounded off as at 15.

In practice the vault is placed in the bottom of the open groove, the casket is lowered into the same.

The groove 14 is filled with a plastic, waterproof cement, such as one having an asphaltum base and the lid is then lowered in place, the portion 9 of the lid fitting into the open top of the vault and the band 10 telescoping down over the outside of the box, while the tongue formed by the protrusion of the pan 12 and the reinforcement 3a being

forced down into the filling of the groove 14, and within the interior of the box 2.

Thus a water-tight seal is formed between the lid and the vault which will not be impaired by cracks in the concrete of either the vault or the lid.

The spacing of the reinforcement away from the surfaces of the metal box and lid and the securing of the reinforcement thereto aids in forming reinforced monolithic structures of great strength and permanency.

In some cases it is customary to place the lid of the vault in the bottom of the grave and then the casket is placed thereon and the inverted vault is lowered down over the casket. In this case the air trapped in the interior of the vault acts as a seal to prevent the entrance of the water between the lid and the vault.

It is evident that my present invention may be applied with great advantage to this type of vault.

What I desire to claim is:—

1. A lid for a burial vault composed of concrete and provided with a continuous groove to receive the upper edge of the vault and having embedded therein an inverted waterproof pan whose lower edge protrudes into said groove which provides a continuous tongue, and metallic reinforcement embedded in the concrete and projecting therefrom around said tongue to cover the same.

2. A burial vault including a body having side and end walls provided with an upwardly facing groove for the reception of sealing material, a cover adapted to fit on said body and extending over said groove, and foraminous metallic reinforcing imbedded in said cover and having a reinforced flanged end extending downwardly from said cover adjacent the edges thereof to enter the groove in the body whereby the sealing material will key with the reinforcing to securely hold the cover and body together.

3. A burial vault including a body having side and end walls provided with an upwardly facing groove for the reception of sealing material, a cover adapted to fit on said body and extending over said groove, foraminous metallic reinforcing imbedded in said cover and extending downwardly from said cover adjacent the edges thereof to enter the groove in the body whereby the sealing material will key with the reinforcing to securely hold the cover and body together, said downwardly extending portion of the reinforcing being doubled back upon itself and having its edge imbedded in the cover, and a metallic flange imbedded in the cover and extending downwardly between the doubled portion of the reinforcing to stiffen the latter.

Signed at Pittsburgh, Pa. this 20th day of July, 1928.

HARRY W. LORESCH.
